WITNESS:

U. C. Deike. INVENTOR

BY Victor J. Evans

ATTORNEY

UNITED STATES PATENT OFFICE

ULRIC C. DEIKE, OF WASHINGTON, DISTRICT OF COLUMBIA.

GOLF CLUB.

Application filed June 7, 1924. Serial No. 718,622.

To all whom it may concern:

Be it known that I, ULRIC C. DEIKE, a citizen of the United States, residing at Washington, in the District of Columbia, have invented new and useful Improvements in Golf Clubs, of which the following is a specification.

This invention relates to improvements in golf clubs and has for an object the provision of a club which will be a material aid to the user in obtaining the proper timing or rhythm which is an essential factor in a properly executed stroke.

In a properly executed stroke, a large arc is described by the head of the club and at some point in this arc the club attains a maximum speed. This point of maximum speed should occur at the time of contact of the club with the ball, but it is exceedingly difficult, especially for the novice, to tell just when this maximum speed occurs.

Usually during a swiftly executed stroke, a swishing sound occurs due to the rapid movement of the club through the air, but it is practically impossible to distinguish at what particular point of the stroke the sound is the loudest and therefore, practically impossible to determine from the sound the point of maximum speed.

The present invention however provides means for accentuating this sound by equipping the club with a whistle which will of course produce its loudest sound at the point of greatest speed, so that the player, with the aid of this whistle may control his stroke in such manner that the club will strike the ball at the proper time.

With the above and other objects in view, the invention further includes the following novel features and details of construction, to be hereinafter more fully described, illustrated in the accompanying drawings and pointed out in the appended claims.

In the drawings:—

Figure 1 is an elevation of the lower portion of the golf club equipped with the invention.

Figure 2 is an elevation looking at the side opposite that shown in Figure 1.

Figure 3 is an enlarged fragmentary sectional view on the line 3—3 of Figure 1.

Figure 4 is a sectional view similar to Figure 3 but illustrating the invention applied to a different type of club.

Figure 5 is a view similar to Figure 1 but

showing a different arrangement of whistle.

Figure 6 is a view showing the type of whistle illustrated in Figure 5 applied to a different type of club.

Referring to the drawings in detail 60 wherein like characters of reference denote corresponding parts, the reference character 10 indicates the head of a club such as a mid-iron. As shown in Figures 1, 2 and 3 of the drawings this head 10 is provided 65 with a recess 11 which extends inwardly from one face thereof and from which extends an opening 12 which is disposed concentric to the recess 11. Secured within the recess 11 is a flanged disk 13 which is provided with an opening 14 which is in a line with the opening 12 so that a whistle is formed which will operate as a signal or indicator when the club is in use.

In Figure 4 of the drawings the head 10^a 75 forms a part of a different type of club, such as a driver and is provided with a recess 15 which extends inwardly from its outer end. This recess communicates with aligned openings 16 which extend transversely through 80 the head 10^a. Located within the recess 15 is a whistle 17 which is held in place by a plug 18.

In Figure 5 the head 10 of the club is the same as that shown in Figures 1, 2 and 85 3 and the whistle which is indicated at 19 is carried by a threaded stud 20 which is secured within the threaded socket provided in the head 10.

The club shown in Figure 6 is the same 90 as that illustrated in Figure 4 and the head 10^a of this club has secured thereto a whistle 19^a which is provided with a tapered threaded stud 21 after the manner of a wood screw so as to provide means for securing the 95 whistle to the club.

It will be apparent from the foregoing description and accompanying drawings that a club equipped with the invention when in use produces a whistling sound, the intensity of which increases in accordance with the rapidity of the movement through the air. By this means the user may tell by the difference in sound whether the head of the club meets the ball at the point of maximum speed of the club, or whether the club meets the ball (or the supposed position of the ball if it is a practice stroke) at exact right angles to the line of flight, or in a twisted position, so as to check the cor- 110

rectness of grip. The invention further serves as a guide for distance for if a ball is driven a hundred yards a certain difference in sound will be produced by the whistle. This sound memorized may be produced again at will by a practice stroke so that when an intended stroke is made a repetition of the previous sound will drive the ball a similar distance. A lesser stroke and consequently a fainter sound will drive the ball a shorter distance and a more vigorous strike producing a louder sound will drive the ball a greater distance. This is valuable in learning the game of golf. Authorities agree that the back swing of the club must be made moderately slow and if a club equipped with the invention is taken back too quickly it will automatically warn the player before the stroke is made. The invention is susceptible of various changes in its form, proportions and minor details of construction and the right is herein reserved to make such changes as properly fall within the scope of the appended claims.

Having described the invention what is claimed is:-

1. The combination with a golf club having a recess in the head thereof and an opening extending transversely through said head from said recess, of a whistle secured within the recess and adapted to be operated by the travel of the club through the air.
2. The combination with a golf club, of an audible signal embedded in the head of the club and adapted to be operated by the travel of the club through the air.
3. In combination with a golf club, a signal device carried thereby, said signal device being operable on both the back and forward strokes of the club to indicate the speed of travel of the club when the latter meets the ball (or the supposed position of the ball during practice) and to indicate approximately the distance of a drive.

In testimony whereof I affix my signature.

ULRIC C. DEIKE.
